(57) **CLAIM**

The ornamental design for a drainage bag cover, as shown and described.

DESCRIPTION

FIG. 1 is a top plan view of a drainage bag cover showing my new design in a flattened condition, with the bottom plan view being a mirror image thereof;

FIG. 2 is a front perspective view thereof, shown in wrapped condition. The broken line showing of a drainage bag tube and hook are for illustrative purposes only and forms no part of the design;

FIG. 3 is a rear perspective view thereof; and,

FIG. 4 is a top plan view thereof.
